UNITED STATES PATENT OFFICE.

ANDREW BROWN, OF PHILADELPHIA, PENNSYLVANIA.

FLUID-ELEVATOR.

SPECIFICATION forming part of Letters Patent No. 774,557, dated November 8, 1904.

Application filed December 16, 1903. Serial No. 185,374. (No model.)

To all whom it may concern:

Be it known that I, ANDREW BROWN, a citizen of the United States, residing in Philadelphia, Pennsylvania, have invented certain improvements in Fluid-Elevators, of which the following is a specification.

My invention relates to certain improvements in apparatus for elevating fluids; and it consists more particularly in an improved form of vertically-placed conveyer designed to receive a container for liquids and after the conveyer has been operated so as to transport the same to a desired point to be so manipulated as to cause said container to be filled with fluid and then be returned to its starting-point.

The objects of the invention are to provide an elevating apparatus of the class noted which, while being efficient in action, shall be easily and inexpensively constructed. It is further desired that the device shall be of such a nature as will not be likely to become inoperative through long continued usage.

Another object of the invention is to provide relatively simple mechanism for conveying a glass, for example, from one room to another beneath it which can be operated to open the valve of a fluid-supply pipe after said glass has been properly placed with regard to the same, it being also desired to provide a device for operating an electric-light switch or equivalent device which may be so arranged as to light a lamp before the valve is turned on and to extinguish said lamp after the valve has been turned off.

These objects I attain as hereinafter set forth, reference being had to the accompanying drawings, in which—

Figure 1 is a sectional elevation showing the preferred arrangement of the parts of my improved fluid-elevator. Fig. 2 is an enlarged side elevation, partly in section, of a portion of the device shown in Fig. 1. Fig. 3 is a plan view of the device shown in Fig. 2. Fig. 4 is a plan view of a portion of my improved fluid-elevator, showing it as constructed to deliver fluid to a container from any one of a number of sources. Fig. 5 is an elevation of my improved elevator, showing it as used in connection with a special form of the valve-

operating mechanism and of the device for operating the lamp-switch. Fig. 6 is an elevation of a special form of a portion of my invention. Fig. 7 is an enlarged sectional elevation of a portion of the structure shown in Fig. 6. Fig. 8 is an enlarged plan view taken on the line 8-8, Fig. 6. Fig. 9 is a side elevation of a possible construction for the valve and spigot operating mechanism; and Fig. 10 is a plan view of the lower end of the tubular carrier-guide, showing the mirror and the electric lamp as supported thereby.

In the above drawings I have illustrated my invention as designed to convey a glass from one level to a lower one, after which it may be operated so as to light a lamp and open a valve in a fluid-supply pipe. When said glass is filled, the device is manipulated so as to close the valve and extinguish the lamp, after which the glass is raised to its original level and removed.

My improved structure is shown as passing through a floor A and is supported partly from this and partly from a framework B, which may be made in any convenient manner, in the present instance consisting of two uprights b and a cross-piece b'.

The frame of the conveyer proper consists, preferably, of a tube C, supported in such forms of the invention as are shown in Figs. 8-9, inclusive, so as to be free to turn on a vertical axis, and having in such case a step-bearing c on the cross-piece b', there being a handle c' fixed to its upper end, whereby it can be turned when desired. There is a slot 85 extending longitudinally of said tube for practically its entire length, and in said slot is mounted a carriage or carrier D, this having a portion d extending within the tube and a portion d', in the form of a tray or receptacle, extending outside of the tube for the reception of a glass. A rope or chain e is connected at one end to the carrier D, from whence it passes over a pulley e', mounted in an opening at the upper end of the tube C, 90 then extends downwardly to a pulley e'', from which is hung a tension-weight e'', these latter parts being preferably suspended below the cross-piece b'. If desired, said rope may include a counterweight D', and there is pref- 100

erably a second pulley c^2 adjacent to the pulley c' for the purpose of guiding the rope so that it will not interfere with the inwardly-extending portion d of the carrier during operation of the device.

A fluid-supply pipe F , connected to a barrel or other source of fluid, passes through the side member b , of the frame B , and in that form of my invention shown in Figs. 1 to 3 is provided with a valve b^2 , to which is attached a vertically-swinging end section b^3 . A downwardly-extending link b^4 connects said end section with a lever b^5 , which in the present instance is fulcrumed to one of the side members b and projects into the path of the glass-carrier D . The end section of the supply-pipe is normally retained in an elevated position, as indicated in dotted lines in Fig. 2, by means of a counterweight b^6 , this being connected to the section b^3 by means of a wire or cord b^7 passing over a pulley b^8 , supported by a side member b of the frame.

An incandescent lamp G is fixed to one of the supporting members b at one side of the tube C and is provided with a reflector g , which not only throws its light onto the carrier and its glass when these are in a position at the bottom end of the tube C , but also cuts off the direct rays of light from an observer at the upper end of said tube. For turning on and off this lamp I provide any desired form of switch mechanism, operated either directly by movement of the guiding-tube C or by movement of the end section b^3 of the supply-pipe. In Figs. 1 to 3 the said mechanism consists of a bar h , having a forked end h' , placed to be engaged by the tube-section b^3 , when this latter is in its elevated position. The opposite end of the bar h is connected to the blade h^2 of the switch H , which is provided with means—as, for example, the spring-pressed plunger h^3 —tending to keep it in a closed position. Said switch is connected in circuit with the lamp G in the well-known manner.

A mirror J is supported on the frame B to one side of the bottom of the tube C and below the lamp G , and by means of said mirror it is possible to obtain a side view of the glass from the upper floor through a suitable opening u therein.

In operating my improved fluid-elevator a glass is placed on the carrier which, it will be understood, is at the upper end of the tube C , and the handle or crank attached to the pulley c' is turned, so as to lower said carrier. This passes downwardly through the opening in the floor, being guided and maintained in an upright position by means of the inwardly-extended portion or head d , which is guided by the slot in the tube C . It will be understood that the counterweight b^6 normally retains the end section b^3 of the fluid-supply pipe in its elevated position and that this section while so held presses against the bar h

and keeps the switch H in an open condition in spite of the action of the plunger h^3 . When, therefore, the carrier D approaches the lower end of the tube C , it engages the projecting end of the lever b^5 and moves this, with the attached tube-section b^3 , downwardly, so that said section extends over the glass. Such movement of the tube-section opens the valve b^2 , with the result that fluid is delivered to the glass. It will be noted that almost immediately after the tube-section b^3 has begun its downward movement the switch H is closed by the action of its spring-pressed plunger h^3 and the lamp G is lighted, so as to enable an observer to see that fluid is properly delivered to the glass, as well as to see when said glass is filled. When the operator notes that the glass is nearly filled and begins to raise the carrier, even though the counterweight b^6 elevates the movable pipe-section b^3 , the switch H is not opened so as to extinguish the lamp until the said pipe-section has reached such a position that the flow of fluid therefrom is completely stopped.

If it be desired to deliver fluid to the glass from any one of a number of different sources, the various parts of the apparatus may be arranged as shown in Fig. 4, in which F' F^2 F^3 are pipes connected to different barrels and each provided with valve-operating mechanism similar to that shown in the other figures. In order that the carrier with its glass may be moved so as to be under the movable end section of any of the various supply-pipes, I support the tube C so that it may be turned by means of its handle c' on a vertical axis, there being a step-bearing for the lower end of said tube, as shown in Figs. 2 to 7.

If desired, the valve mechanism for the fluid-supply pipe may be of the form shown in Fig. 5, in which the end section b^3 of the said pipe is made to swing horizontally to operate a valve and to bring it into position over the glass. For the purpose of moving said section the tube C is provided with a projecting lug c^4 , which is connected to the swinging pipe-section by means of a link c^5 .

In order to permit movement of the vertical tube without corresponding movement of the carrier and its glass, I construct the lower end of said tube, as shown in Figs. 6 to 8, with an inner section C' , which is slotted to correspond to the longitudinal slot in the main tube. Said main tube has a portion of its lower end removed so as to permit its revolution on a vertical axis through an arc of ninety degrees, it being understood that the tubular section C' , which does not turn, properly supports the glass-carrier without permitting motion of the same. The above-mentioned arc of motion is usually sufficient to operate the valve and switch mechanism hereinafter described.

The lamp-switch may be positively operated by the movement of the tube C' by means of the device shown in Fig. 5, in which

the switch H' has pinned to its blade a reciprocable bar h⁴. This bar is carried in openings through the framework B and is provided with projecting lugs h⁵, which are engaged by a bar fixed to the tube C². In using this form of my invention when the operator finds that the carrier has reached the lower limit of its motion at the bottom of the tube C² he turns said tube by means of the handle c', so as to swing the arms c⁷ and c⁴ through arcs of ninety degrees. This results in a longitudinal movement of the rod h⁴, which closes the switch connected thereto and lights the lamp G and also swings the pipe-section b⁹ so that its open end is over the glass. Since such turning opens the valve b², liquid will flow into the glass until it is stopped by a reverse movement of the tube C².

If desired, the end section of the pipe F 20 may be made immovable, in which case the guide-slot in the vertical tube is curved, as illustrated at C³, Figs. 6 and 7, so as to move the carrier around and under said end section of the pipe as it is being lowered. The flow of 25 liquid from the pipe is then caused by rotation of the tube C³, this being transmitted therefrom to the valve in said pipe by means of a link c⁸, which connects a projecting arm of the said tube C³ with an arm c⁹, fixed to said 30 valve. Again, as shown in Fig. 9, the valve in the fluid-supply pipe might be operated by motion of the end section thereof, as in Figs. 1 to 3, and said section may be connected directly from the tube C through the arms and 35 link c⁸, as above indicated.

In constructing my device so as to have a number of sources of supply for fluid available I may support both the mirror J and the lamp G from the tube C, as illustrated in 40 Fig. 10, so that these parts, while moving with the said tube, always remain in the same position relatively to the carrier and its glass. Hence it is always possible to ascertain the amount of liquid in the glass while it is being 45 filled, irrespective of the position of the pipe from which said fluid is drawn.

I claim as my invention—

1. In a fluid-elevator, the combination of a carrier, a guide structure for the same, a supply-pipe, means for controlling the flow of fluid therefrom, a lamp, and a switch having means placed to coact with said carrier for controlling the action of said lamp, substantially as described.

55 2. In a fluid-elevator, the combination of a substantially vertical tube having a longitudinal slot, a carrier movable therein, a fluid-supply pipe, means for moving one of the members comprised by the carrier and said 60 pipe so as to bring the latter into a predetermined relation to a container on said carrier, with means for controlling the flow of fluid from said pipe, substantially as described.

3. In a fluid-elevator, the combination of a 65 carrier, a guide therefor, a pulley on said

guide, a flexible connection extending over the pulley and connected to the carrier, a fluid-supply pipe, a valve therein and means operated by the carrier for opening said valve, substantially as described.

70 4. In a fluid-elevator, the combination of a carrier, a guide therefor, means for moving said carrier on the guide, means for filling a container on said carrier, said means including a supply-pipe, with an electric switch, and a lamp controlled thereby, said switch having means whereby it is operated by motion of the said movable supply-pipe, substantially as described.

75 5. In a fluid-elevator, the combination of a carrier, means for guiding the same, means for causing motion of the carrier, a movable supply-pipe having a controlling-valve, means for operating said valve, an electric lamp, a switch therefor, means for moving the supply-pipe and means connecting the supply-pipe with the switch, said latter means being placed to cause closing of the switch before the valve-operating means will permit flow of fluid and to cause extinguishing of said lamp 80 only after said valve has been closed, substantially as described.

85 6. The combination of a guide, a carrier movable thereon, means for causing motion of the carrier, a fluid-supply pipe, a valve therein, a piece placed to be engaged by the carrier and means for connecting said piece with the valve, substantially as described.

90 7. The combination of a guide, a carrier movable thereon, means for causing motion 100 of the carrier, a fluid-supply pipe, a valve therein, said pipe having a movable section, a movably-supported arm placed to be engaged by the carrier, means for connecting said arm and the section of the pipe and means for normally retaining the pipe in a position out of the path of the carrier, substantially as described.

105 8. The combination of a guide, a carrier movable thereon, means for causing motion of the carrier, a fluid-supply pipe having a movable section and a valve, a weight connected to said movable section and tending to maintain it in an elevated position out of the path of the carrier, and means operated by the carrier for causing the movable section to be brought over a receptacle on the carrier and for operating the valve, substantially as described.

115 9. The combination of a switch having 120 means normally tending to close it, a lamp electrically connected thereto, a fluid-supply pipe having a movable section and a valve, means for normally retaining the said section in a position to hold the switch open, a carrier for a receptacle, a guide for the carrier, means operated by said carrier for causing release of the switch and for moving the said section of pipe over the carrier and means for operating the valve, substantially as described.

10. The combination of a tubular guide, a carrier movable thereon, a device for moving said carrier, the same including a flexible connection attached to the carrier and extending 5 in the tube, with means for maintaining tension on said flexible connection, a supply-pipe and means for supplying fluid therefrom to a receptacle on the carrier, substantially as described.
11. The combination of a longitudinally-slotted tube, a carrier having a portion movable in said slot, a pulley on the tube, a flexible connection between the pulley and the carrier, a second pulley provided with a weight 10 and engaging the said flexible connection with a fluid-supply pipe and means for controlling the flow of fluid therefrom to a receptacle on the carrier, substantially as described.
12. In a fluid-elevator, the combination of 15 a carrier for a container, means for moving the same, a fluid-supply pipe having a valve and mechanism operatively connected to the valve but having a portion placed to be actuated from the carrier at a certain point of its path of motion to operate the valve, substantially as described.
13. In a fluid-elevator, the combination of 20 a carrier, means for moving the same, a plurality of fluid-supply pipes, each having a valve and a device for each pipe placed to contact with the carrier for operating at will the valve on any one of said pipes, substantially as described.
14. In a fluid-elevator, the combination of 25 a carrier, means for moving the same, a plurality of fluid-supply pipes, each having a valve and a movable arm connected to said valve, with means for causing the carrier to engage any desired one of said arms to operate the valve connected thereto, substantially as described.
15. The combination of a guide movable on its longitudinal axis, a carrier movable on the guide, a plurality of fluid-supply pipes, each having a valve and an arm connected thereto, 40 with means for moving said guide so as to cause the carrier to engage any desired one of the arms and thereby operate the valve to which it is connected, substantially as described.
16. The combination of a slotted tube movable on its longitudinal axis, a carrier movable in the slot of said tube, a plurality of fluid-supply pipes, each having a movable section, a valve, an arm connected to said valve, 45 with means for causing the carrier to engage any one of said arms, substantially as described.
17. The combination of a vertically-movable carrier, a fluid-supply pipe having a section movable into and out of the path of motion of said carrier, an arm in the path of motion of said carrier and connected to said section, with a valve operated by the movement of said arm, substantially as described.
- In testimony whereof I have signed my name to this specification in the presence of two subscribing witnesses.
